3 Sheets-Sheet 3

UNITED STATES PATENT OFFICE.

HENRY MÜLLER, OF PHILADELPHIA, PENNSYLVANIA.

WINDOW.

Application filed September 22, 1926. Serial No. 136,906.

My invention relates to windows having sliding sashes.

Windows in the upper stories of buildings and in lower stories which are a considerable distance above the ground are difficult to clean on the outside; the customary manner being to clean the inner side of the panes and then to sit or stand on the narrow ledge outside the window to clean the outer side of the panes, a proceeding which is distasteful to all women and exceedingly dangerous for some.

Attempts have been made to overcome this disadvantage but the devices so far produced require specially built window frames or extensive alterations of the window parts and thus are not adapted to ready installation on windows in use.

One of the objects of my invention is to produce means whereby any ordinary sliding sash may be swung inwardly for the purpose of cleaning.

Another object is to provide means which may be inexpensively manufactured and readily installed on windows in existing structures.

These objects, and other advantageous ends which will be described hereinafter, I attain in the following manner, reference being had to the accompanying drawings, in which

Figure 1 is an inside elevation of an ordinary window embodying a preferred form of my invention,

Figure 2 is a section on line 2—2 of Figure 1,

Figure 3 is a view of the inside of the frame, taken on line 3—3 of Figure 1,

Figure 4 a similar view taken on line 4—4 of Figure 1, and

Figure 5 a perspective view of the window shown in Figure 1, but with the sash swung into position for cleaning.

Figure 6 is a hook adapted to suspend the lower sash when same is to be swung,

Figure 7 a weight stop forming part of my invention,

Figure 8 another view of the weight stop, and

Figure 9 a sectional view taken through the right hand weight box and showing a method of installing the weight stops.

Referring now to all the views simultaneously, 10 represents the weight boxes, 11 the sill and 12 the lintel of an ordinary win-

dow in which lower sash 13 and upper sash 14 are slidably mounted; the lower sash being mounted between the inner beads 15 and parting beads 16 and the upper sash 14 being mounted between the parting bead 16 and the outer bead 17. As windows of this character are so generally well known, it will not be further described.

In carrying out my invention I remove the parting bead from the left side of the frame and substitute therefor a round rod 18 of nearly the same diameter as the thickness of the parting bead. The rod 18 is secured in place by having its ends projecting into holes bored in the lintel and sill 19 and by a U-shaped strap secured to the casing near its center, as shown at 19 in Figures 2 and 3. Two eye pieces 20 are slipped on the rod before same is installed. One of the eye pieces is attached to the head rail 21 and the other to the bottom rail 22 of the sash 14.

A hole 23 is bored in the inside casing strip 24 of the left hand weight box 10 to receive the enlarged portion 25 of the hook 26 and a notch, smaller in cross section than the diameter of the hole 23 and of the enlarged portion 25 of the hook 26, is formed in the left hand bead 15 to accommodate the shank of the hook 26. The hole 23 is bored in the casing strip 24 at a point slightly above the normal position of the head rail 28 of the lower sash 13. A screw eye 27 is secured to the top rail 28 a short distance from the left hand side of the sash.

Referring now more particularly to Figures 7, 8 and 9, 29 represents the body part of a weight stop in which is formed a longitudinal slot 30. The reduced portion 31 of a rod 32 is mounted in the slot 30 and held in place by nuts 33 threaded to the end of the reduced portion. The weight stop is made in two preferred forms; that shown in Figures 7 and 8 has a bent handle 34 secured to one end of the body part while that shown in Figure 9 has a straight handle 35 secured at or near the end of the body part. The slot 30 is provided in the weight stops in order that the rod 32 may be adjusted to fit weight boxes of different shapes and sizes. Slots 36 are cut in the pulley piece of the right hand weight box slightly below the highest point to which the weights may be raised and holes are bored through the inside casing strip and transversely of

the pulley piece so as to intersect the bottom ends of the slots 36. The body part 29 of a weight support is inserted in each of these holes and a rod 32 secured to the body part, as shown in Figure 7, the rod being adjusted so that it is located in the center of the weight box. Strips 37 are then tacked across the upper ends of slots 36 to prevent the rods 32 from falling outwardly. Rods 32 are of such length that, when turned inwardly, their ends will rest against the inside of the rear wall of the weight box and support the window weights.

If it is desired to dispense with the handles 34 on the inside of the window casing, a slot is cut in the edge of the inside casing strip intersecting and extending below the hole bored for the body part 29 and the handle 35 screwed into the body part 29 after same has been installed. The rod 32 is raised to a vertical position by depressing the handle 35.

The right hand inside bead 15 is cut just above the top of the bottom bead as shown at 38 and at a point a short distance above the top of the bottom sash as shown at 39. Hinges 40 are connected to the cut-out portion 41 so that same may be swung outwardly as shown in Figures 1, 4 and 9.

The right hand parting bead 16 is cut near its lower end and center at points opposite points 38 and 39 on inside bead 15 and the cut-out portion 42 mounted on hinges 43 so that this portion may be swung outwardly as shown in Figure 5. The hinges 43 preferably have a wire extension on one leaf and are set in grooves in the face of the pulley piece.

When it is desired to clean the outside of the sash, the lower sash 13 is raised a short distance, the hook 26 pulled to its outermost position and the sash then lowered which will bring the hook 26 in engagement with the screw eye 27. The cut-out portion 41 of the right hand bead is swung inwardly on the hinges 40 and the cut-out portion 42 swung inwardly on the hinges 43. The upper sash 14 is then pulled downwardly until the eye piece 20, on the head rail 21, comes in contact with the top of the U-shaped strap at 19 and the bottom of the sash strikes the stop 44, which will bring the bottom of the sash but a short distance above the top of the lower inside bead on the frame. The sash cords 45 are then pulled outwardly until the weights are in their uppermost position and the rods 32 swung, by means of the handles, across the weight boxes. The sash cords are then released and the rods 32 support the weights so that the cords 45 are slack enough to allow the windows to be swung inwardly. The hook 26 and eye 27 act as a hinge at the top of the lower sash. The bottom of the sash needs no hinge as it bears against the pulley piece

between the left hand bead 15 and the rod 18. The eyes 20 which are fastened to the top and bottom rails of the upper sash 14 and encircle the rod 18 act as hinges for the upper sash. In case the sash cord pulleys 46 are so loosely mounted that there is danger of the sash cord slipping out of their grooves when the windows are swung inwardly, I provide staples 47 immediately below the pulleys 46 through which the sash cord 45 runs. Where it is necessary to install the staples 47, it is sometimes necessary to relieve the outside of the right hand stiles of each sash in order to clear the staples when the sash is in its uppermost position.

After the sashes have been cleaned, the upper sash is swung back into position, the parting strip portion 42 swung into place, then the lower sash swung into the frame, the weights pulled into their uppermost position and the rods 32 swung upwardly by means of handles 34 or 35. Bead section 41 is then swung into place, the lower sash slightly raised, the hook 26 pushed to its innermost position and the window closed.

Where the weight support shown in Figures 7 and 8 is used, the rod 32 is held in its upright position by means of any suitable catch placed on the inside casing strip. Where a weight support with a handle 35 is used, the handle 35 is pushed downwardly and held in place by the bead section 41. The holding means described for both handles 34 and 35 are only to guard against accidental displacement of the rod 32, as it normally rests against the strips 36 which brings the center of gravity of the rod 32 to the left of the axis of the body part 29.

It will thus be seen that my invention consists in applying a number of separate parts to any window having a sliding sash, that it facilitates the cleaning of the sash and obviates the necessity of sitting or standing on the narrow ledge outside the window.

While I have described the parts of my invention as taking particular forms and have illustrated and described them as being applied to the most common type of window, it will be readily understood that modifications might be made in the parts and the invention adapted to different applications without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A window including a frame, a sliding sash counterbalanced by a weight, a socket on the sash, a hook movably mounted in the frame and adapted to engage the socket, an

inner bead hinged to the frame, and means to support the weight near its uppermost position.

2. A window including a frame, a pair of sashes counterbalanced by weights and adapted to slide in vertical parallel grooves in both sides of the frame, a rod between one pair of the grooves, a sectional parting bead between the opposite pair of grooves, 5 hinges attaching one of the parting bead sections to one side of the frame, an inner bead hinged to the same side of the frame, and means to hinge the sashes to the opposite side of the frame.

15 3. A window including a frame, a pair of sashes counterbalanced by weights and adapted to slide in vertical parallel grooves, a rod between one pair of the grooves, a sectional parting bead between the opposite 20 pair of grooves, hinges attaching one of the parting bead sections to one side of the frame, an inner bead hinged to the same side of the frame, means to hinge the sashes to the opposite side of the frame, and means 25 to support the weights near their uppermost positions.

4. A window including a frame, sashes 30 slidably mounted in a pair of grooves formed in the frame, an inner bead and a parting bead hinged to one side of the frame, a rod adapted as a parting bead and

secured between the grooves on the opposite side of the frame, eye pieces hinging the upper sash to the rod, an eye piece secured to the top rail of the lower sash, and a hook 35 movably mounted in the frame and adapted to engage the eye piece on the lower sash.

5. A window including a frame, sashes 40 slidably mounted in a pair of grooves formed in the frame, an inner bead and a parting bead hinged to one side of the frame, a rod between the grooves on the opposite side of the frame, eye pieces hinging the upper sash to the rod, an eye piece secured to the top rail of the lower sash, a hook mov- 45 ably mounted in the frame and adapted to engage the eye piece on the lower sash, and means to support the weights near their uppermost positions.

6. In combination with a window of the 50 class described, a weight supporting member having a body part with a slot therein, a weight supporting member mounted in the slot, and a handle secured to the body part.

7. Adjustable means adapted to be positioned in combination with a window frame 55 for supporting a sash weight in a desired position independent of the position of the sash.

In testimony whereof I have signed my 60 name to this specification.

HENRY MÜLLER.
